UNITED STATES PATENT OFFICE.

HENRY C. EGERTON, OF PASSAIC, NEW JERSEY, ASSIGNOR, BY MESNE ASSIGNMENTS, TO WESTERN ELECTRIC COMPANY, INCORPORATED, A CORPORATION OF NEW YORK.

ELECTRIC AMPLIFIER.

1,207,384.

Specification of Letters Patent.

Patented Dec. 5, 1916.

Application filed August 15, 1914. Serial No. 856,971.

To all whom it may concern:

Be it known that I, HENRY C. EGERTON, a citizen of the United States, residing at Passaic, in the county of Passaic and State 5 of New Jersey, have invented certain new and useful Improvements in Electric Amplifiers, of which the following is a full, clear, concise, and exact description.

This invention relates to electric amplifiers of the type used, for example, in announcing systems to receive and transmit with increased intensity electric currents of telephonic and musical frequencies, and more particularly it relates to a type of amplifier in which an electromagnet receiving the current to be amplified acts upon an armature which serves to vibrate a resistance-varying or transmitter element.

The objects of the invention are, first, to provide an improved magnet system whereby increased sensitiveness of the amplifier may be secured; second, to provide an improved structure and mounting for the transmitting elements which will effectively 20 radiate the heat generated in the resistance-varying medium; and third, to provide an improved organization of circuits and apparatus by means of which a number of amplifiers may be conveniently operated from any available source of direct current, which 25 is particularly desirable for installations of this nature.

In the magnet system of my improved amplifier, instead of the usual permanent magnet an iron core is magnetized by windings which are connected in the same circuit which feeds the transmitter elements, and in order to prevent singing of the amplifier these magnet windings are connected 30 to have a differential effect with respect to the armature so that changes in this current have no effect upon the armature, which is, however, actuated in response to currents in another set of windings also upon the same 35 core. The magnetizing windings are also connected so as to be non-inductive with respect to the actuating windings.

The core is preferably E-shaped, and the energizing windings are arranged to magnetize the outer arms of the core to the same polarity. The armature is centrally pivoted upon or adjacent to the central arm of the core, and the actuating windings, which re-

ceive the current to be amplified, are disposed upon the outer arms of the core, but 55 are so wound that variations in the current received will tend to strengthen one of the outer poles and weaken the other, and in this manner cause the armature to be vibrated.

The transmitter element preferably comprises two resistance-varying mediums, both actuated by the single armature and electrically connected to give what has been called a "push and pull" effect. In order to 65 provide an effective radiation of heat, I preferably mount the metallic cups of these transmitter elements in actual contact with a substantial metal base, and the movable elements, which are carried upon the armature lever, are insulated from said armature lever and from each other.

Where it is desired to install a number of loud speaking telephones for announcing purposes, usually the most convenient source 75 of current is an ordinary lighting circuit; and a further feature of my invention consists in an arrangement such that the energizing circuits including the energizing magnet windings of the several amplifiers, 80 are connected in series, so that they serve as protecting resistances for each other, while at the same time effectively supplying different groups of telephone receivers.

The invention will be more particularly 85 described, and further features thereof pointed out in connection with the accompanying drawings, in which—

Figure 1 is a vertical cross-sectional view of an amplifier incorporating the improvements of this invention; Fig. 2 is a horizontal section of the essential elements of the amplifier taken along line 2—2 of Fig. 1; Fig. 3 is another view of the same taken along line 3—3 of Fig. 1; Fig. 4 shows in 90 enlarged form a detail of the motor or receiver element of the amplifier; Fig. 5 shows in an enlarged form a detail of the generator or transmitter element of the amplifier; Figs. 6 and 7 show, in perspective, contact 95 and supporting means for removably mounting the amplifiers in question on a panel-board and for associating a plurality of the said amplifiers together in a single system; Figs. 8, 9, 10 and 11 show schematically different novel circuit arrangements which may 100

be employed with the amplifiers, and Fig. 12 shows schematically a complete amplifying system in which a plurality of amplifiers are operated by a master transmitting station, each amplifier in its turn operating a plurality of loud-speaking receivers.

Referring in detail to the drawings, a brass containing case, comprising a base portion 1, cylindrical portion 2 and cover 3, incloses and supports by means of screws 4 an irregularly shaped brass block 5, which serves as a mounting base for the transmitter and receiver elements of the amplifier. In one portion of block 5 a bore, or cylindrical hole 6, is provided; at either end of this bore a brass cylinder 7 is inserted. Cylinder 7 has an annular inner projection 8 with an upturned edge 9. The inner surface of edge 8 is provided with an insulating coating 10 of enamel, paper, or other suitable material, and forms the wall of a chamber containing comminuted resistance varying material 11, such as granular carbon. The rear opening of the said chamber 15 is closed by a carbon disk 12, which is held in place against the shoulder formed by projection 8, by a spring member 13. A clamp 14 fastened to block 5 by screws 15 holds the spring 13 under compression. A 20 felt washer 16 rests against the edge 9 and forms a flexible cushion on which a carbon disk 17 is held. Screws 18 pass through the centers of disks 17 into a threaded insulating bushing 19 in one end of a lever arm 20. Bushing 19 is preferably made of mica, as it has been found that this material can readily be threaded, and produces a very strong bushing if the grain of the material runs at right angles to the plane 25 of the thread. Disks 17 are further insulated from lever arm 20 by washers 21, preferably of mica. Cylinders 7 may be adjusted with respect to disks 17 so as to insure an effective closure of the carbon chambers with the required compression of the felt washers 16, and when so adjusted may be locked into place by screws 22. Light, flexible copper strips 23 are clamped between carbon disks 17 and mica washers 21 30 and serve as connecting terminals for the said disks. The association of the carbon disks 17 with the lever arm 20 in the manner disclosed in Fig. 5 provides a vibrating system of particular value in a differential transmitter element of the type herein described, inasmuch as by insulating the movable electrodes from one another, it is possible to associate the carbon-containing chambers in intimate conducting relation 35 with the brass block 5, which thus acts as an efficient medium for radiating heat away from the transmitter elements and insuring uniform operation thereof. The other end of lever arm 20 carries an armature 24, 40 which is fastened thereto by screws 25.

Armature 24 is beveled from either end in such a way as to form a central transverse ridge 26, which acts, in cooperation with the central pole 27 of a tri-polar magnet system 28, as a fulcrum for lever 20. Magnet system 28 is composed of a plurality of E-shaped punchings 29 of thin sheet iron fastened together between blocks of iron 30 by rivets 31. The unit thus formed is clamped between lugs 32 and 33 by screws 34, which pass through lug 32, block 30 and laminations 29 and thread into lug 33. Lug 32 is made somewhat thinner than lug 33 so as to possess a certain amount of elasticity, whereby it may adapt itself to slight 70 differences in the thickness of the magnet unit and insure a firm and rigid clamping thereof.

The special features of the magnetic circuit of the motor or receiver element which are shown in Fig. 4 are of particular value. In structures of this general character it has been customary in the past to grind a plane surface on the armature and to obtain the necessary separation between the said armature and the lateral pole-pieces of the magnet by providing a protruding angular or curved ridge on the central pole of the magnet, said ridge serving as a fulcrum on which said armature rocks and being of the required height to provide the necessary air-gap between the armature and said lateral poles. While such a structure can be made very efficient, it is not so desirable as the structure shown in Fig. 4, because of the difficulty of accurately grinding the surface of the lateral and central poles to the desired relative heights. The use of the beveled armature 24 makes it possible to grind the pole 27 flush with poles 35, an operation 90 which can be performed with manufacturing facility and accuracy. The beveling of the armature is also easily accomplished. The structure shown in Fig. 4 is therefore a decided improvement over preceding 100 structures in that its greater facility of manufacture insures greater accuracy and uniformity in the manufactured product.

Located on poles 35 are spools of wire 115 36 and 37. Two spools are shown on either pole, but in certain cases, to be discussed later, it is desirable to use a greater number of spools. A bifurcated spring 38 fastened to block 5 by screws 39 holds these spools in place and prevents them from coming into contact with armature 24. Armature 24 is held against pole 27 by two springs or reeds 40 of hardened steel, each having at one end a knife-edge extension 41 which acts as a fulcrum or point of support 120 against block 5, and having at its other end a reed-like extension 42 bearing a hemispherical brass knob 43, which rests on armature 24 with a degree of pressure adjustable by means of screw 44, which passes 130

through 40 and threads into block 5. Screw 44 may be locked in position by screw 45. Spring members 40 are necessary in order to give to the vibrating system of the amplifier the required elasticity, and their tension is normally adjusted so as to maintain substantially equal air-gaps between the ends of the armature 24 and the poles 35. Armature 24 may be provided with longitudinal slots 46 to decrease the eddy-current losses therein.

As a combined means for mounting the amplifier and connecting it in circuit, the base 1 carries terminal buttons 47 and 48 insulated therefrom by bushings 49 of hard rubber and washers 50 of mica, buttons 47 and 48 being held in place by nuts 51 on the threaded shanks 52 of said buttons, said nuts also clamping in place soldering terminals 53. Buttons 48 differ from 47 in that they have necks 54 and heads 55 adapted to fit into button slots 56 in channeled busbars 57 mounted on a slate panel 58, or other suitable means of support. Mounted on either side of and between busbars 57 are contact springs 59. Button slots 56 have enlarged ends 60 to permit the insertion of heads 55. The other ends of slots 56 have posterior recesses 61, in which heads 55 are designed to rest and be held in locked engagement by the pressure of springs 59 against buttons 47. The arrangement just described is particularly adapted to announcing systems, where a large number of loud-speaking receivers are operated from a master transmitting station through intermediate amplifiers, and provides a simple means for replacing individual amplifiers with a minimum interruption of the service.

The amplifier above described is used in an improved circuit shown in Fig. 8. Here direct current from battery 62 flows through windings 37 in series, stationary electrodes 12, granular carbon 11, movable electrodes 17, retardation coil windings 63 and protecting resistance 64, back to battery. Windings 37 are so connected that currents flowing therein magnetize poles 35 with like polarity and pole 27 with the opposite polarity, whereas windings 36 are so connected that currents flowing therein tend to magnetize poles 35 with opposite polarities. It is thus seen that alternating currents entering windings 36 from line conductors 65 will cause armature 24 to rock back and forth on its fulcrum 26. No resultant current will be induced in windings 37 by the currents in winding 36, inasmuch as windings 37 are non-inductively connected with respect to windings 36 and similarly alternating or pulsating currents in windings 37 produce no rocking motion on armature 24. The arrangement of the windings 36 and 37 just described is desirable in that it permits the use of the same current to en-

ergize the transmitter element of the amplifier that is used to magnetize the receiver element, and this without danger of local oscillations commonly spoken of as "singing."

The operation of the transmitter element is that of the well-known "push and pull," or differential transmitter, wherein two transmitter buttons are customarily used and connected with a sound-receiving diaphragm, or other vibrating medium, in such a way that an increase in the resistance of one button is accompanied by a simultaneous decrease in the resistance of the other. Several methods of associating such a transmitter with an output circuit are possible. One form is shown in Fig. 8, where 66 is the primary of an induction coil and 67 the secondary winding thereof, connected to outgoing line conductors 68. The retardation coil windings 63 are of high impedance and are connected inductively in series, so as to cause a minimum shunting effect on primary winding 66. Fig. 9 shows another form of circuit which may be used, the only difference between the circuit of Fig. 9 and that of Fig. 8 being that current is fed to the transmitter element through the middle point of induction coil primary 66, instead of through retardation coil windings 63.

In some classes of service to which the amplifier of this invention is applicable, where the input energy is small, there may be a tendency for the transmitter element to pack, and it has therefore been found desirable to provide some means for automatically regulating the division of current between the two transmitter buttons. Fig. 10 shows a means of accomplishing such regulation. In this case, windings 37 instead of being connected inductively in series, as in Fig. 8, are connected non-inductively in series. Current from battery 62 is led into windings 37 at their junction point 69, through windings 37 in parallel, and therefore serves as in Fig. 8 to magnetize poles 35 with like polarity. The current then flows through retardation coil windings 63 in parallel, through electrodes 17, granular carbon 11 and electrodes 12 in parallel, to common point 70, thence through protecting resistance 65, back to battery 62. Any tendency toward inequality in the resistances of the two transmitter buttons will be accompanied by an inverse difference in the current flowing therethrough, and consequently in the magnetization of the two poles 35. By connecting the different elements together after the manner shown in Fig. 10, the unequal pull on the two ends of the armature 24, due to this inequality of magnetization, may be made to expand and increase the resistance of the button of lower resistance, simultaneously contracting and lowering the resistance of the higher resistance.

button, and thereby restoring the current equilibrium.

It has been found that the connections shown in Fig. 10 effectively prevent any noticeable current unbalance and any objectionable packing. This degree of regulation is however attended by somewhat of a decrease in the efficiency of the amplifier. Where a lesser degree of regulation is permissible, the combination of the magnetizing systems of Figs. 8 and 10, which is shown in Fig. 11, may be employed. The operation of this circuit will be evident from the discussion just given in connection with Figs. 8 and 10.

An announcing system of loud-speaking receivers, making use of the amplifier circuits of this invention, is shown in Fig. 12, where a plurality of loud-speaking receivers 71 are operated simultaneously from a single transmitting station 72 through a bank of amplifiers A, B, Z. Station 72 may be a voice transmitting station or a music transmitting station, as desired. The dotted portions of this figure show those parts of the system which are included in the amplifier elements themselves. The actuating windings 36 of the receiver elements of the different amplifiers A, B and Z are connected in parallel across busbars 57 by the button terminals 48, which lock into slots 56 as described above. The electrodes 17 are connected to the two outer spring terminals 59, and one terminal of magnetizing windings 37 is connected to the central spring terminal 59 through button terminals 47 as described. It will be noted that the magnetizing windings 37 and the transmitter elements of the amplifier of the different groups A, B and Z are arranged in series with a single source of current supply 62. This arrangement makes possible the operation of a considerable number of amplifiers with a comparatively low consumption of current, and it further makes possible an efficient consumption of such current, especially where derived from the commercial direct current lighting mains, inasmuch as the individual elements while effectively functioning as amplifiers, at the same time serve as protecting resistances for each other.

Referring further to Fig. 12, current from battery 62, one pole of which is grounded, flows by way of central spring 59 of the first group A, through magnetizing windings 37, common point 70, electrodes 12, granular carbon 11 and electrodes 17, in parallel, to outer terminal springs 59. Permanently connected across outer terminals 59 is the induction coil primary 66, in parallel with retardation coil windings 63. From outer terminal springs 59 therefore the current flows through retardation coil windings 63, in parallel to common point 73, which is

permanently connected to central spring 59 of second group B. In a similar manner current flows through amplifiers of group B and each succeeding group to last group Z, the common point 73 of which is connected through protecting resistance 64 to ground, thus completing the battery circuit.

What is claimed is:

1. In an electric amplifier, an electromagnet, actuating windings and magnetizing windings for said electromagnet, said magnetizing windings being non-inductively connected with respect to said actuating windings, and a transmitter element in circuit with said magnetizing windings. 80

2. In an electric amplifier, an electromagnet with a central pole and two lateral poles, an armature pivotally resting on said central pole, means for maintaining normally equal air-gaps between the two said lateral poles and said armature, and a transmitter element operated by said armature. 85

3. In an electric amplifier, an electromagnet having a central pole and two lateral poles, an armature with a central transverse ridge, said ridge resting on said central pole and acting as a pivot for said armature, and a transmitter element operated by said armature. 90

4. In an electric amplifier, an electromagnet, actuating windings and magnetizing windings for said electromagnet, a transmitter element in circuit with said magnetizing windings, an armature for said electromagnet responsive to currents in said actuating windings and non-responsive to transmitter currents flowing through said magnetizing windings. 95

5. In an electric amplifier a receiver element comprising an electromagnet, actuating windings and a plurality of magnetizing windings therefor, said magnetizing windings being non-inductively connected with respect to said actuating windings, and a differential transmitter element comprising 100 a plurality of transmitter buttons, each of said transmitter buttons being in circuit with one of said magnetizing windings. 110

6. In an electric amplifier, a receiver element comprising an electromagnet having a central pole and two lateral poles, an armature pivotally borne upon said central pole, actuating windings and magnetizing windings on said lateral poles, said magnetizing windings being non-inductively connected with respect to said actuating windings, and a transmitter element in circuit with said magnetizing windings. 115

7. In an electric amplifier, an electromagnet with a central pole and two lateral poles, an armature pivotally resting on said central pole, means for maintaining normally equal air-gaps between the two said lateral poles and said armature, a transmitter element, a vibrating electrode mem- 125

130

ber therefor, and an arm operatively connecting said armature with said electrode member.

8. In an electric amplifier, a receiver element comprising an electromagnet having a central pole and two lateral poles, an armature pivotally borne upon said central pole, actuating windings and magnetizing windings on said lateral poles, said magnetizing windings being non-inductively connected with respect to said actuating windings, a transmitter element in circuit with said magnetizing windings, a vibrating electrode member for said transmitter element, and an arm operatively connecting said armature with said electrode member.

9. In an electric amplifier, an electromagnet, an armature therefor, a metal block with a transverse bore, two distinct carbon-¹⁰ containing chambers oppositely disposed and adjustably located within said bore and each having an electrode in good heat-conducting contact with the metallic walls of said bore, a lever arm fastened to said armature and extending between said chambers, two carbon disks attached to opposite faces of said lever arm insulated therefrom and from each other and functioning as movable electrodes for said carbon chambers.

10. In an amplifier system, an electromagnet, actuating windings and magnetizing windings for said electromagnet, said magnetizing windings being non-inductively connected with respect to said actuating windings, a transmitter element, and a source of direct current serially in circuit with said transmitter element and said magnetizing windings.

11. In an amplifier system, an electromagnet, actuating windings and magnetizing windings for said electromagnet, a transmitter element, a source of direct current serially in circuit with said transmitter element and said magnetizing windings, an armature for said electromagnet responsive to currents in said actuating windings and non-responsive to transmitter currents flowing through said magnetizing windings.

12. In an amplifier system a receiver element, comprising an electromagnet, actuating windings and a plurality of magnetizing windings therefor, said magnetizing windings being non-inductively connected with respect to said actuating windings, a differential transmitter element comprising a plurality of transmitter buttons, and a battery supply circuit with two branches, each branch including one of said transmitter buttons and one of said magnetizing windings.

13. In an amplifier system, an electromagnet, magnetizing windings therefor, an armature associated with said electromagnet, a differential transmitter element comprising a plurality of transmitter buttons,

a common vibrating system for said transmitter buttons operatively connected with said armature, a battery supply circuit with two branches, each branch including one of said transmitter buttons and one of said magnetizing windings, said magnetizing windings co-operating with said armature to maintain substantially equal currents in said transmitter elements.

14. In an amplifier system, a receiver element comprising an electromagnet having a central pole and two lateral poles, actuating windings and magnetizing windings on said lateral poles, said magnetizing windings being separate from, and connected non-inductively with respect to said actuating windings, an armature with a central transverse ridge, said ridge resting on said central pole and acting as a pivot for said armature, means for maintaining normally equal air-gaps between the two lateral poles and said armature, a transmitter element with two oppositely disposed electrode chambers, movable electrodes therefor, a lever arm operatively connecting said armature with said movable electrodes, said electrodes being insulated from each other and from said lever arm, and a source of direct current serially in circuit with said magnetizing windings and said transmitter element.

15. An amplifier system comprising a master transmitting station, a plurality of amplifiers having transmitter elements and receiver elements, actuating windings and magnetizing windings for said receiver elements, a source of direct current, means for connecting said actuating windings in circuit with said master station, and other means for connecting said transmitter elements serially in circuit with said magnetizing windings and said source of direct current.

16. An amplifier system comprising a master station, busbars connected to said master station, a plurality of amplifiers having receiver elements and transmitter elements, actuating windings and magnetizing windings for said receiver elements, said actuating windings being connected in parallel across said busbars, a source of direct current, and means for connecting said magnetizing windings and said transmitter elements in series with one another and with said source of direct current.

17. An amplifier system comprising a master station, busbars connected to said master station, a plurality of current amplifiers having receiver elements and transmitter elements, said receiver elements being detachably connected in parallel across said busbars, a source of direct current, and resilient means for connecting said transmitter elements in series with one another and with said source of direct current.

18. In an amplifier system, busbars, button slots in said busbars, a plurality of current amplifiers, contact buttons on said amplifiers adapted to enter into and lock in said button slots, other contact devices on said amplifiers, resilient means mounted adjacent to said busbars and adapted to make frictional contact with said contact devices and to hold said contact buttons in locked engagement with said busbars.

19. An amplifier system comprising a master transmitting station, busbars electrically connected to the terminals of said master station, button slots in said busbars, a plurality of current amplifiers each containing a transmitter element and a receiver

element, terminal buttons for said receiver elements adapted to enter into and lock in said button slots, contact terminals for said transmitter elements, spring members 20 mounted adjacent to said busbars and adapted to make frictional contact with said contact terminals and to hold said contact buttons in locked engagement with said busbars.

25

In witness whereof, I hereunto subscribe my name this 12 day of August A. D., 1914.

HENRY C. EGERTON.
